HOLDER FOR A MULTIPLE DRINKING STRAW

Daniel Hunter Howes, Darien, Conn.

Application March 12, 1957, Serial No. 45,225

Term of patent 3½ years

(Cl. D2—3)

I claim:

The ornamental design for a holder for a multiple drinking straw, as shown.
